UNITED STATES PATENT OFFICE

2,210,473

COMBUSTION PROMOTING DEVICE

Joseph C. Testa, Long Beach, Calif.

Application July 6, 1936, Serial No. 89,228

1. Claim. (Cl. 277—64)

This invention relates to combustion promoting devices for internal combustion engines, and has more particular reference to certain new and useful improvements in the device disclosed in 5 the U. S. Patent to A. P. Sollender No. 1,324,281 granted December 9, 1919.

The primary object of the present invention is to generally simplify and improve the device of the above-mentioned patent.

Another more specific object of the present invention is to provide manually operable means for regulating the maximum amount of air admissible through the air inlet openings of the fitting which is interposed in the conduit that 15 connects the water circulating system of the engine with the intake manifold of the latter.

Still another object of the present invention is to provide such an air admission controlling or regulating means which is simple in construction, efficient, and constructed to effectively 20 maintain the adjustments thereof.

Other objects will appear as the nature of the invention is better understood, and the same consists in the novel form, combination and arrangement of parts hereinafter more fully described, shown in the accompanying drawings and claimed.

In the drawing:

Figure 1 is a view showing the present device 30 in elevation and partly broken away.

Figure 2 is a view similar to Figure 1 with parts broken away and in section.

Figure 3 is a section on line 3—3 of Figure 2.

Figure 4 is a section on line 4—4 of Figure 35 2; and

Figure 5 is a fragmentary elevational view showing a modified form of fitting constructed in accordance with the present invention.

Referring in detail to the drawing, a fragment 40 of the intake manifold of an internal combustion engine is indicated in Figures 1 and 2 at 5, while a fragment of the water circulating system of the engine is indicated at 6. The present device includes an elbow 7 for insertion in the intake manifold 5, a fitting including a tubular casing 8 in which a valve 9 is yieldingly held seated by a spring 10.

As in the above-mentioned patent, the valve 9 is preferably conical and closes both of two spaced ports 11 and 12, by the resilient effect of the spring 10. Also, as generally shown in said patent, one or more openings 13, open to the atmosphere, are provided in the casing 8, between the ports 11 and 12 for the admission of air. The usual conduit 14 is provided for con-

necting the fitting with the part 6 of the water circulating system, the latter being facilitated by means of a suitable end connection member 15 on one end of the conduit 14. A valve 16 that may be suitably controlled from the instrument board of an automobile, is provided for controlling the flow of water or moisture through the conduit 14 to the manifold 5. However, instead of providing this valve on the end of the conduit 14 which connects with the part 6 of the water circulating system, it is arranged at and coupled to the other end of the conduit 14 adjacent the casing 8, as at 17. The casing 8 is formed integral with the other end of valve 16, thus providing a single fitting embodying both 15 the valve 16 which is manually operable and the valve 9 with its associated parts. One end of the elbow 7 is adjustably threaded into the outer end of casing 8 for varying the strength of the spring 10, the adjusted relation of the elbow 7 and the casing 8 being secured by a lock nut 18.

While not shown herein, it is to be understood that the intermediate portion of the conduit 14 is to be wound around the exhaust pipe of the engine or otherwise suitably heated.

In accordance with the present invention, the air inlet openings 13 are in the form of longitudinal elongated slots in the casing 8, and a sleeve valve 19 is provided and longitudinally adjustable on the casing 8 for regulating the degree of opening of the slots 13 and thereby regulating or controlling the maximum amount of air admissible through said slots 13. Suitable means is provided for preventing accidental longitudinal shifting of the sleeve valve 19 relative to the casing 8 so that it will remain in any of its adjusted positions until manually adjusted. Obviously, it is important to make this provision in a device placed upon an automobile and subject to being disturbed by vibration or otherwise. A most efficient construction is had by threading an end portion of the valve 19 on the outer end portion of the casing 8, the inner end portion of the casing 8 being provided with a smooth cylindrical external surface engaging a corresponding internal surface in the inner end portion of the sleeve valve 19 as shown more clearly in Figure 2. However, even a threaded adjustment is such as to allow accidental turning and consequent longitudinal shifting of the sleeve valve 19 under certain conditions, and for this reason additional means is preferably provided for resisting accidental rotation of the valve 19. As shown in Figures 1 to 4 inclusive, this means 55

5 may consist of a suitably shaped spring band 20
disposed in an annular external groove 21 pro-
vided in the outer surface of the smooth inner
end portion of the casing 8 and having spaced
6 portions alternately contacting the surface of the
casing 8 at the bottom of such groove and the
inner surface of the adjacent end portion of
valve 19. By properly regulating the rigidity of
10 the spring 20, it may offer the desired frictional
resistance to turning of valve 19, as will be ap-
parent.

15 However, as shown in Figure 5, the means for
preventing accidental turning of valve 19 may
take other forms. In Figure 5, this means con-
sists of a spring tongue 22 struck from the inner
end portion of the valve 19a and adapted to en-
gage in any one of the slots or openings 13 when
20 aligned therewith. The arrangement is such that
the tongue 22 may be forcibly moved out of the
slot by manual turning of the valve 19a with
appreciable force, the inner surface of the tongue
22 being slightly rounded or beveled to avoid a
25 positive lock. Otherwise, the device of Figure 5
corresponds to that of Figures 1 to 4 inclusive,
and will be similarly used with the other parts
of Figures 1 and 2 in a complete device.

25 The present invention operates in exactly the
same way as the device of the patent mentioned
above, except that the valve 16 is differently po-
sitioned and the valve 19 is provided to regulate
30 the maximum amount of air admissible through

the air inlet openings 13. It will be seen that a
more definite proportion of air and moisture will
be had by the present improvement, while the
re-arrangement of parts provides for more ready
5 manufacture and simplification of the construc-
tion as disclosed in said patent. Minor changes
may be made without departing from the spirit
and scope of the invention as claimed.

What I claim as new is:

10 In a combustion promoting device of the char-
acter described, the combination of a fitting hav-
ing an opening extending axially therethrough
and a pair of spaced internal valve seats and lon-
gitudinally elongated openings leading to the at-
mosphere and opening into said axial opening 15
between said spaced valve seats, a pipe member
threaded into one end of said fitting, a recipro-
cable valve fitting both seats, a spring interposed
between said pipe member and said valve for
normally holding said valve on said seats, and a 20
manually operable sleeve valve having its upper
portion threaded on the outside of said fitting
for adjustment longitudinally of the latter to
regulate the amount of air admissible through
said elongated openings, the lower portion of said 25
sleeve valve being snugly fitted about said fitting
adjacent said elongated openings whereby to con-
trol the size of said openings as said sleeve is
rotated.
